CLAIM

The ornamental design for a cargo support for the bed of a truck or the like, as shown.

DESCRIPTION

FIG. 1 is perspective view of a cargo support for the bed of a truck or the like showing my new design;

FIG. 2 is a bottom perspective view thereof;

FIG. 3 is an end elevational view thereof; and,

FIG. 4 is a perspective view thereof taken from the opposite side and end to FIG. 1.

Fig. 1

Fig. 2

FIG. 3.

FIG. 4.
